UNITED STATES PATENT OFFICE.

ROBERT G. SCHNEE AND FRED W. RILEY, OF CLEVELAND, OHIO, ASSIGNEES TO THE REPUBLIC MAUSOLEUM COMPANY, OF CLEVELAND, OHIO, A CORPORATION OF OHIO.

BURIAL DEVICE.

1,247,338.

Specification of Letters Patent. Patented Nov. 20, 1917.

Application filed March 20, 1913. Serial No. 755,718.

To all whom it may concern:

Be it known that we, ROBERT G. SCHNEE and FRED W. RILEY, citizens of the United States, residing at Cleveland, in the county of Cuyahoga and State of Ohio, have invented a certain new and useful Improvement in Burial Devices, of which the following is a full, clear, and exact description, reference being had to the accompanying drawings.

This invention relates to burial devices, and has in view generally the provision of a device of this character which will insure an efficient circulation of air through a mausoleum or vault and in spaces surrounding the crypts and at the same time permit of the employment of self-contained crypts therein, each crypt being so constructed and equipped that its interior will be provided with a germicide-laden atmosphere sufficient in quantity, quality and duration to disinfect completely such interior and prevent the formation of gases of decomposition. In addition, each crypt will be provided with a moisture absorbent which is capable of maintaining the interior of and the atmosphere within the crypt completely dry during the entire period of desiccation. A further object of the invention is to provide a crypt which is self-contained and entirely independent in action and operation from any other crypt in the vault or mausoleum. A further object of the invention is to provide a process whereby remains may be quickly dried or desiccated and the atmosphere surrounding the same completely sterilized.

With the foregoing objects in view, the invention may be defined further and more generally as consisting of the combinations of elements embodied in the claims hereto annexed and illustrated in the accompanying drawings wherein Figure 1 represents a fragmentary vertical sectional view of a vault or mausoleum constructed in accordance with this invention, the view being taken substantially on the line 1—1 of Fig. 2; Fig. 2 a vertical sectional view corresponding approximately to the line 2—2 of Fig. 1; Fig. 3 an elevation and Fig. 4 a vertical sectional view of a trap which is employed with each crypt for the purpose of controlling the escape of gases therefrom; Fig. 5 a perspective view of one of the disinfesting elements or cartridges; and Fig. 6

a similar view of one of the containers for the moisture absorbent.

Describing by reference characters the various parts illustrated herein, 1 denotes the floor and 2 the roof of the vault or mausoleum. In one of the wings 3 a series of crypts is shown, the crypts being preferably of concrete and represented at 4. Each crypt is provided with a bottom 5 having one or more recesses 6 extending substantially the full length thereof, said recesses being located at the central portion of the bottom and being filled with the moisture absorbing material 7. While three such recesses are shown in the drawing, the number is not material and may be varied as desired. For the moisture-absorbing material, calcium oxide is preferred, and this may be and preferably is contained within shallow, elongated metal containers 7^a which will fit in the recesses. Each container is hermetically sealed, the cover 7^b being soldered in place and provided with a tongue adapted to be engaged by a key 7^c to strip off the cover and expose the calcium oxide when the crypt is placed in use.

In the drawings three double tiers of crypts are shown, the double tiers having at each side thereof a vertically extending air passageway 8, which passageways communicate at their tops with a horizontal duct 9 communicating at its central portion with a passageway 10 having grated discharge outlets 11 at opposite ends thereof. The bottoms of the passageways 8 communicate with a horizontal air conduit 12 which is preferably embedded in the floor 1 and communicates at one end with the atmosphere, as shown at 13. This conduit communicates with the passageways 8 by means of ports 14.

One side wall of each crypt extends along and preferably defines part of a passageway 8. This side wall is provided with a trap which permits of the escape of any gases that may accumulate within the crypt when the pressure of such gases is sufficiently high. Each trap is conveniently formed by means of a pair of symmetrical lead plates 15 (see Figs. 3 and 4) each having depressions in their meeting faces adapted to receive a glass receptacle of generally U-shape, the lead plates, when joined together, constituting a protecting casing for the glass receptacle. The glass receptacle comprises a short lateral inlet branch 16 and a down-

wardly extending vertical branch 17. The opposite vertical branch of the U shaped receptacle is of relatively small cross-sectional area, as shown at 18, and these branches are connected by a transverse bottom branch 19 which diminishes in cross-sectional area from the branch 17 to the branch 18. At a suitable distance above the bottom branch 19, an inclined branch 20, which is also of relatively small cross-sectional area, extends upwardly from the branch 17 and merges with the upper end of the branch 18, the branch 18 above its junction with the branch 20 discharging into a common lateral outlet 21. The lateral inlet branches 16 and 21 are protected by means of surrounding casings or hubs 16^a and 21^a, respectively, which extend substantially flush with the outer ends of the said lateral branches to protect the same. A trap comprising the parts 15 to 21^a inclusive will be embedded within a cement side wall 8 of each crypt, with the inlet connection 16 in communication with the interior of the crypt and the outlet connection 21^a communicating with a passageway 8^a. By this construction, each crypt is hermetically sealed at all times against the inflow of gaseous fluids and is hermetically sealed against the outflow of such fluids except through the pressure-controlled trap.

Each crypt is shown as having a casket 22 therein, which may be of any ordinary construction except that the bottom thereof will be provided with openings 23 above the recesses 7. These openings, as so located, insure the complete drying of any gases or vapors that may be given off from the body. In fact, in place of an uncovered casket, any other suitable ventilated support may be used for the remains. The lower portion of the trap will be filled with mercury, indicated at 19^a, to a point above the junction of the branches 17 and 20, whereby a seal will be provided to prevent the escape of gases through the branch 20 until a pressure is attained sufficient to displace the mercury to about the level indicated by the line a—a in Fig. 3. The small cross-sectional area of the vertical branch 17 enables the desired pressure to be produced against the escape of the gases without the employment of a large quantity of mercury. It is believed that decomposition will be so prevented or retarded that there will be practically no discharge of gases through the trap. Should a sufficient pressure be produced within a crypt, however, the trap affords a sealed safety valve for the escape of excess gases,— rendered innocuous, however, by saturation with the germicidal gas.

The disinfecting agent is put up in the form of a cartridge 24, which is preferably placed in the crypt at one side of the casket 65 therein. This cartridge consists of an ab-

sorbent 25, such as asbestos, which is saturated with a solution of a volatile disinfectant, preferably formaldehyde, the saturated absorbent being contained within a sheet metal casing or box. When ready for use, the top of the casing will be perforated, as shown at 26, by any suitable tool. This disinfecting cartridge, if made in about the proportions shown in the drawings, will be amply sufficient to furnish all the disinfectant necessary to completely sterilize the atmosphere of the crypt and any gases of decomposition that may be formed. Under no ordinary conditions, however, will such gases be evolved, decomposition being prevented and the remains being thoroughly desiccated.

From the foregoing construction it will be apparent that an efficiently ventilated burial vault is realized and a construction of crypt provided that will secure the absorption of all moisture and maintain a dry sterilizing atmosphere therewithin with the result that the remains are quickly dried or desiccated, the decomposition reduced to a minimum if not absolutely prevented, and the escape of noxious gases avoided. Furthermore, each crypt is complete and self-contained, has no connection with and is independent of every other crypt, and, through the materials employed and the construction and arrangement of parts, a cheap but effective method of sterilizing and desiccating is attained.

The process of disinfecting which is accomplished in each crypt forms the subject matter of our divisional application No. 788,548, filed September 8, 1913.

Having thus described our invention, what we claim is:

1. In a mausoleum, the combination of a plurality of crypts, each crypt being sealed whereby it is out of communication with the other crypts, means within each crypt for maintaining the atmosphere dry, means within each crypt for supplying to such atmosphere volatile disinfecting agent, and pressure controlled means connected with each crypt for venting the same.

2. A burial crypt having in a wall thereof a trap, said trap having an inlet branch adapted to communicate with the interior of the crypt and being provided in the wall with a downwardly extending branch, a substantially horizontal branch, an upwardly extending branch, and an upwardly inclined branch connecting the first mentioned vertical branch and the upper portion of the second vertical branch, said trap having a laterally extending outlet branch projecting through the wall of the crypt, and liquid in the lower portion of said trap adapted to seal the upwardly inclined branch.

3. A burial crypt having in a wall thereof a trap comprising a pair of metal plates

having their meeting faces hollowed out for the reception of a substantially U shaped trap, said plates having oppositely projecting hubs, one of said hubs extending to the 5 inner surface of the crypt wall and the other hub extending to the outer surface of the crypt wall, a glass receptacle having vertical branches connected at their bottoms by a substantially horizontal branch, an upwardly inclined branch extending from the lower part of one of the vertical branches to the upper part of the other vertical branch, mercury in the lower portion of the trap adapted to seal the bottom of the inclined branch, the vertical branch with which the lower end of the inclined branch communicates being provided with a laterally extending inlet connection and the opposite vertical branch having an outlet connection extending laterally in the opposite direction from the inlet connection, said plates enclosing the said glass receptacle and the lateral hubs thereof protecting the inlet and outlet connections one of said hubs extending to the inner surface of the crypt 20 25

wall and the other hub extending to the outer surface of the crypt wall.

4. A burial crypt having in a wall thereof a trap, said trap having an inlet branch adapted to communicate with the interior of the crypt and being provided in the wall with a downwardly extending branch, an upwardly extending branch, and an upwardly inclined branch connecting the first mentioned branch with a portion of the second branch which is located above the lower end of the inclined branch, said trap having an outlet branch communicating with the outer surface of the crypt wall, there being liquid in the lower portion of the trap adapted to seal the upwardly inclined branch. 30 35 40

In testimony whereof, we hereunto affix our signatures in the presence of two witnesses.
